United States Patent Office.

WILLIAM EDGAR TWINING, OF MORRISON, ILLINOIS.

Letters Patent No. 76,006, dated March 24, 1868.

IMPROVED CAR-COUPING.

The Schedule referred to in these Letters Patent and making part of the same.

TO ALL WHOM IT MAY CONCERN:

Be it known that I, WILLIAM EDGAR TWINING, of Morrison, in the county of Whitesides, and State of Illinois, have invented a new and useful Improvement in Car-Couplings; and I do hereby declare that the following is a full, clear, and exact description of the same, reference being had to the annexed drawings, making part of this specification, in which the coupling is shown in perspective.

My improvements consist, first, in attaching to the link a handle, by which it can be held without exposing the person coupling the cars to the danger of having his hand crushed between the draw-heads; and, secondly, in the form given to the draw-head, by which the link is held securely without using a coupling-pin.

In the annexed drawings, A is the link, which is the ordinary coupling-link with handle A' attached, projecting on each side of the centre. The handle should be long enough to enable the person coupling the car to hold the link in the proper position to enter the draw-head without being exposed to the danger of having his hand crushed between the draw-heads or buffers. B is the draw-head, which I construct as shown. The hook B¹ is curved back to hold on its under side the link A. Two recesses, B² and B³, are formed in the back of the draw-head. The link, being introduced through the open space in the top of the draw-head, cannot escape while the cars remain on the track, for, on being relaxed by the cars coming together, the link will be pressed back either into the recess B², or, rising along the slope of the hook B¹, it will enter recess B³, the top of which is carried so far forward that the link can only escape when lifted vertically, which can only occur by hand, or when one of the cars is thrown from the track, so as to push the link nearly vertically. The link may be used with the ordinary pin-coupling.

What I claim as my invention, and desire to secure by Letters Patent, is—

The draw-head B, constructed with the hook B¹, and recesses B² and B³, arranged substantially as described.

In testimony whereof, I have signed my name to this specification in the presence of two subscribing witnesses.
